UNITED STATES PATENT OFFICE.

JAMES W. KELLY, OF CHICAGO, ILLINOIS.

DESIGN FOR A CLOSET-SCREEN.

No. 39,631.

Specification for Design.

Patented Oct. 20, 1908.

Application filed April 9, 1908. Serial No. 426,153. Term of patent 14 years.

To all whom it may concern:

Be it known that I, JAMES W. KELLY, a citizen of the United States, residing at Chicago, in the county of Cook and State of Illinois, have invented a new, original, and ornamental Design for a Closet-Screen, of which the following is a specification, reference being had to the accompanying drawing, forming a part thereof, which shows a perspective view of said design.

The salient features of the design thus shown consist in the partition walls of the closet screen radiating from the central pipe and the ornamental brackets and braces, by means of which the partitions are rigidly held in position.

I claim:

The ornamental design for a closet screen, as shown and described.

JAMES W. KELLY.
